214,097

BRACKET FOR ATTACHING STROBOSCOPIC FLASH ATTACHMENT

Martin S. Ackerman, East Hills, N.Y., assignor to Perfect Film & Chemical Corporation, Manhasset, N.Y., a corporation of Delaware

Filed Oct. 18, 1967, Ser. No. 9,060

Term of patent 14 years

Int. Cl. D16—07

U.S. Cl. D61—1

FIG. 1 is a front elevational view of a bracket for attaching a stroboscopic flash attachment to a photographic camera embodying my new design;

FIG. 2 is a top plan view thereof;

FIG. 3 is a bottom plan view thereof;

FIG. 4 is a rear elevational view thereof;

FIG. 5 is a right side elevational view thereof;

FIG. 6 is a left side elevational view thereof; and

FIG. 7 is a perspective view of the bracket for attaching a stroboscopic flash attachment to a camera on a reduced scale.

The broken line in FIG. 1 representing a camera is for the purpose of illustration only.

I claim:

The ornamental design for a bracket for attaching a stroboscopic flash attachment, as shown and described.

References Cited UNITED STATES PATENTS

D. 181,712	12/1957	Dreyfuss	-----	D61—1
D. 184,849	4/1959	Bradd et al.	-----	D61—1
D. 186,248	9/1959	Parker	-----	D61—1
2,783,696	3/1957	Sewig.
D. 165,783	1/1952	Pennock et al.	-----	D61—1
1,874,813	8/1932	Saunders.
1,896,898	2/1933	Hildebrand	-----	248—300 X

EDWIN H. HUNTER, Primary Examiner.

N. C. HOLTJE, Assistant Examiner.